UNITED STATES PATENT OFFICE.

JOHN H. LEECH, OF BRIDGEPORT, CONNECTICUT, ASSIGNOR TO E. H. H. SMITH, OF NEW YORK, N. Y.

DESIGN FOR A SPOON OR FORK HANDLE.

SPECIFICATION forming part of Design No. 32,381, dated March 27, 1900.

Application filed February 24, 1900. Serial No. 6,419. Term of patent 3½ years.

To all whom it may concern:

Be it known that I, JOHN H. LEECH, a subject of Her Majesty the Queen of Great Britain, residing at Bridgeport, in the county of 5 Fairfield and State of Connecticut, have invented and produced a new and original Design for Spoon or Fork Handles, of which the following is a specification, reference being had to the accompanying drawing, forming 10 part thereof.

As shown in the drawing, the contour of the handle is composed of intersecting curved lines formed by the various ornaments. Beginning at the base of the shank 2 there is a 15 narrow border bead 3 at each side edge up as far as the middle ornaments composed of scroll-like leaflets 4. Above these there is a conventional stem 5 at each side edge, forming a border bead, the upper ends of which 20 bead has the inwardly-turned leaflets 6. In-

side of the stem 5 and leaflets 6 and substantially parallel thereto is an inner stem or bead 7, with a leaflet at its upper end. The tip of the handle has a central trefoil 8 and two scroll figures 9 with their convex sides meeting each other. The middle portion of the handle between the ornaments has a slightly-convex surface. The reverse side of the handle is the same as that herein shown, excepting that the central portion is concave instead of convex. 25

Having described my invention, what I claim as new, and desire to secure by Letters Patent, is—

The design for a spoon or fork handle, as 30 herein shown and described.

JOHN H. LEECH.
